(57) **CLAIM**

The ornamental design for a bipolar electrosurgery actuator system, as shown and described.

DESCRIPTION

FIG. 1 is a perspective view of a bipolar electrosurgery actuator system, showing my new design, with an actuator, a set of forceps integrated with the actuator, and an electrical connection extending from the actuator in a direction away from the forceps;

FIG. 2 is a top plan view thereof;

FIG. 3 is a bottom plan view thereof;

FIG. 4 is a right side elevational view thereof;

FIG. 5 is a left side elevational view thereof.

FIG. 6 is an enlarged rear elevational view thereof; and, FIG. 7 is an enlarged front elevational view thereof.

The broken lines shown in the figures are included for the purpose of illustrating portions of the bipolar electrosurgery actuator system and form no part of the claimed design. The broken away symbol in the drawings indicate that any portion of the article beyond what is shown forms no part of the claimed design.

1 Claim, 7 Drawing Sheets
